UNITED STATES PATENT OFFICE.

FREDERICK RAY, OF SHORT HILLS, NEW JERSEY, ASSIGNOR TO ALBERGER PUMP AND CONDENSER COMPANY, OF NEW YORK, N. Y., A CORPORATION OF NEW YORK.

JET CONDENSING APPARATUS.

1,160,652.

Specification of Letters Patent. Patented Nov. 16, 1915.

Application filed April 29, 1912. Serial No. 693,970.

To all whom it may concern:

Be it known that I, FREDERICK RAY, a citizen of the United States, residing at Short Hills, in the county of Essex and 5 State of New Jersey, have invented certain new and useful Improvements in Jet Condensing Apparatus, of which the following is a specification, reference being had thereto in the accompanying drawing.

10 My invention relates to a jet condensing apparatus of the type having a centrifugal removal pump, and contains numerous novel features of construction and combination, particularly a condensing chamber of spiral 15 form, whereby the steam condensed flows through a passage of gradually decreasing cross-section until the non-condensable vapors are finally removed.

The object of the invention is to make 20 more efficient and economical the construction of centrifugal jet condensers, and to adapt the same for use in many places where the ordinary jet condensing apparatus has not been found as efficient as could be desired.

The invention comprises not only a spiral condensing chamber, but also means for maintaining a constant level of water in the tail-pipe, and also numerous other valuable 30 features of construction, combination and arrangement, substantially as will be hereafter described and then more particularly pointed out in the claims.

In the accompanying drawing illustrating 35 my invention, Figure 1 is a vertical section of my improved steam condensing apparatus. Fig. 2 is a horizontal sectional plan on the line 2, 2, of Fig. 1. Fig. 3 is a horizontal section on line 3, 3, of Fig. 1. 40 Fig. 4 is an enlarged vertical sectional detail view taken on the line 4, 4, of Fig. 3.

Similar characters of reference designate corresponding parts throughout the different figures of the drawing.

45 The condenser shell 1 is mounted on the tail-pipe 2, from which the water is removed by pump 3, said pump being a centrifugal pump and having suction pipe 18 and discharge 19. Exhaust steam enters shell 1 at the inlet 4, while the injection water enters 50 through the pipe 5. The water flowing into the condenser through pipe 5 passes upwardly through the elbow 6 into the top of the shell 1, where it spreads over a tray or plate 7 which is provided with a number of open-

ings 8 that convert the plate 7 into a skeleton or grid-like construction giving ample opportunity for the cooling water to drop down through the shell at a large number of different points in the surface of plate 7. 60 Such a form of tray which allows the water to fall over the edges and through the openings may be greatly modified in the actual practice of the invention, and is not necessary to the successful working of the other 65 features of the apparatus, since various forms of jets or spraying devices might be employed instead, but I have presented such tray here as a convenient and effective device for the purpose. It should also be 70 noted that other horizontal trays or grids at different elevations below the top one may be utilized and in many instances will be found advisable for the purpose of breaking up the vertical flow of water, but this is a 75 mere matter of detail, and is not essential to the invention, and changes in this respect may be made within wide limits without affecting the underlying principles on which I am working.

The exhaust steam which enters at the inlet 4 flows around through the spirally-shaped condensing chamber 9 which, as indicated in Fig. 3, is formed by the outer cylindrical wall of shell 1 and the eccentric inner wall 20. These two walls together form a vertical chamber which gradually decreases in size and terminates at a point where the cross-section is the smallest, as shown at 10. This passage gives a cross-section which varies approximately in proportion to the quantity of steam to be condensed at each point, which is the ideal condition to be aimed at. The water falls from the tray 7 through the spiral chamber 9 and thoroughly condenses the steam, the water of condensation falling into the tail-pipe 2. Finally, the air and non-condensable vapors are removed at the point 11 where the connection is made with the vacuum pump. 90 This connection is more clearly shown in Fig. 4 where the connection is indicated as provided with an inwardly and downwardly projecting perforated pipe 12 which occupies a position in an inner chamber 21 formed by wall 20 having an opening or openings 22 through which the air and vapors pass from the small end of spiral chamber 9. Thus the air and non-condensable vapors can be drawn into pipe 12 by 100 105 110

the vacuum pump whose connection is attached to the outlet 11.

A feature of the invention to which I desire to call attention, and on which I wish to lay considerable stress, is the maintenance of a constant level of water in the tail-pipe 2. This tail-pipe as will be seen by reference to Fig. 1, has a large storage reservoir which is a novelty, being quite distinct from the usual small tail-pipe. The constant level of water which is kept in the tail-pipe 2 is made possible by means of a float 13 on a lever 14, and suitable connecting rods 15 arranged in conjunction with a balanced valve 17 which throttles the supply of steam to either the steam turbine or the engine that drives the centrifugal removal pump 3, for removing water from the tail-pipe 2. When the water level rises in the tail-pipe 2, the regulating valve 17 will be opened slightly, and the speed of the centrifugal pump thereby increased, and the result of this will be that more water will be pumped and the water level will again be reduced until the point of equilibrium is reached which is thus maintained. The object of this is to keep a constant head of water on the pump, so that the pump operates showly as a water pump, the air freeing itself from the surface of the water in pipe 2 and rising in chamber 21 and entering perforated pipe 12 and being removed by the vacuum pump. The pump in this way works under the most efficient conditions possible, whereas in the usual type of centrifugal condenser, the tail-pipe is made small at or about the same diameter as the suction of the pump, so that a large amount of air is carried down with the water thus giving poor material for the pump to work with.

The operation is as follows:—The steam to be condensed enters the spiral chamber 9 through the inlet 4 and courses around through the chamber until it reaches the smallest end 10 thereof. During this passage through the spiral chamber it is condensed by the water falling from the tray 7 through the openings 8. The spiral chamber enables the largest amount of steam and the largest amount of water to be brought together. As the quantity of steam diminishes in traveling around through the chamber, which is itself constantly diminishing in size, the amount of water supplied for the condensation is likewise correspondingly decreasing, and this method enables a most effectual condensation to take place so that by the time the steam reaches the smallest end of the spiral chamber it will practically all have been condensed and there will be very little but air at that point. The air and uncondensable vapors, as I have pointed out, pass from the spiral chamber at the point 10 through the opening or openings 22 into the inner chamber 21, and are drawn

off by the dry vacuum connection. This air chamber 21 also receives the air which is released from the surface of the volume of water in the tail-pipe 2. The lower end of the air chamber 21 enters the water of the tail-pipe, as shown in Fig. 1, and enables a water seal to be formed at that point, and also prevents steam from entering the lower end of the chamber 21.

Many changes may be made in the precise construction and combination of the various parts of my invention without exceeding the scope of the claims, and I reserve the liberty of modifying and changing the exact details of construction and combination as much as may be found necessary to adapt the invention for practical use in a great variety of locations.

Having thus described my invention, what I claim as new and desire to secure by Letters Patent, is:—

1. In a jet condenser, the combination of a cylindrical shell, an inner eccentric wall, said wall and shell together forming a spiral condensing chamber, means for allowing air from the small end of the spiral chamber to enter the interior of the chamber formed within the inner eccentric wall, and means for removing the air from said chamber.

2. In a jet condenser, the combination of a cylindrical shell, an inner eccentric wall, said inner wall and shell together forming a spiral condensing chamber, means for allowing air to pass from the small end of the spiral chamber into the chamber formed by the inner wall, and a tail pipe receiving the lower end of the inner air chamber.

3. In a jet condenser, the combination with a spiral chamber formed by an outer wall and an inner wall, the latter inclosing an interior air chamber which receives air from the small end of the spiral chamber, and means for removing air from said interior chamber.

4. In a jet condenser, the combination of a spiral chamber formed by an outer wall and an inner eccentric wall, the latter inclosing an interior air chamber, and an apertured air removal pipe in said air chamber.

5. In a jet condenser, the combination with a spiral chamber formed by an outer wall and an inner wall, the latter inclosing an interior air chamber, said chamber receiving air from the small end of the spiral chamber, and a tail pipe receiving the lower end of said air chamber so that air may escape thereinto from the condensing water and the water of condensation.

6. In a jet condenser, the combination with a spiral chamber formed by an outer wall and an inner wall, the latter inclosing an interior air chamber, of means for allowing air to pass into said interior air chamber from the small end of the spiral chamber.

ber, and means comprising an air removal pipe in said interior air chamber for withdrawing the air therefrom.

7. In a jet condenser, the combination 5 with a spiral chamber formed by an outer wall and an inner wall, the latter inclosing an interior air chamber having openings to permit the entrance of air thereinto from the small end of the spiral chamber, and air 10 removal means within said interior air chamber.

8. In a jet condenser, the combination of 15 a spiral chamber formed by an outer wall and an inner wall, the latter inclosing an interior air chamber whose wall is perforated to receive air from the spiral chamber, and a perforated pipe supported in said air chamber and connected with a dry vacuum pump.

20 9. In a jet condenser, the combination of a spiral condensing chamber formed by an outer wall and an inner wall, the latter inclosing an inner air chamber whose wall is perforated to receive air from the spiral 25 chamber, a perforated pipe supported in said inner chamber and connected with a dry vacuum pump, and a tail pipe receiving the lower end of the air chamber.

10. In a jet condenser, the combination 30 with a spiral chamber formed by an outer wall and an inner wall, the latter inclosing an inner air chamber having openings to permit the passage of the air thereinto from the spiral chamber, an air removal device 35 supported in said air chamber and having

openings to allow the air to pass thereinto, said device being connected with a dry vacuum pump, and a tail pipe receiving the lower end of the air chamber.

11. In a jet condenser, the combination 40 with a spiral condensing chamber formed by an outer cylindrical shell and an inner eccentric wall, the latter inclosing an interior air chamber having inlet openings for the air from the spiral chamber, a perforated removal pipe within the air chamber 45 which is connected with a pump, and a tail pipe receiving the lower end of the air chamber.

12. In a jet condenser, the combination of 50 a spiral condensing chamber formed by an outer wall and an inner wall, the latter inclosing an interior air chamber, an air removal pipe in said chamber, and a tail pipe of substantial size which receives the lower 55 end of said chamber.

13. In a jet condenser, the combination with a spiral chamber formed by an outer wall and an inner wall, the latter inclosing an interior air chamber, which chamber is 60 provided with inlet means for the air from the spiral chamber, and air removal means in said air chamber.

In testimony whereof I affix my signature in the presence of two witnesses.

FREDERICK RAY.
